HOISTING APPARATUS

Lloyd R. Kalmbach, West Englewood, N. J., assignor to Western Electric Company, Incorporated, New York, N. Y., a corporation of New York

Application July 13, 1939, Serial No. 284,165

7 Claims. (Cl. 254—142)

This invention relates to hoisting apparatus, and more particularly to apparatus for hoisting articles for mounting on a frame.

In the manufacture of telephone equipment various electrical elements are mounted on shelves in the factory and transported to the place, such as a telephone exchange, where they are mounted upon vertical frames. Shelves with the electrical elements mounted thereon necessitate the use of a hoist in lifting them to the position of mounting and in holding them while they are being secured to the frame. Due to the fact that the frames are frequently disposed in rows, leaving only narrow aisles therebetween, with each frame in most instances extending almost to the ceiling and conditioned to support separate shelves of electrical elements of which care must be taken not to damage, it has been found difficult and oftentimes impossible to mount the shelves with the conventional hoisting methods and apparatus.

With this and other objects in view, the invention comprises a hoisting apparatus having a lateral unit and a vertical unit, the lateral unit being removably secured upon the top of a frame and having sheaves for a hoisting cable adjustable relative to the frame, the vertical unit having uprights removably secured to the frame and the lateral unit and supporting a winch for moving a cable for lifting articles, such as shelves, having electrical elements mounted thereon in position for securing to the frame.

Other objects and advantages will be apparent from the following detailed description when taken in conjunction with the accompanying drawings, wherein

Fig. 1 is a perspective view illustrating the hoisting apparatus associated with a frame for lifting articles in place for mounting on the frame;

Fig. 2 is a side elevational view of the lateral unit;

Fig. 3 is a fragmentary detailed view of the lateral unit;

Fig. 4 is a fragmentary side elevational view of the means to secure the vertical unit to the lateral unit, portions thereof being shown in section;

Fig. 5 is a fragmentary front elevational view of the securing means shown in Fig. 4, this view being taken substantially along the line 5—5 of Fig. 4;

Fig. 6 is a fragmentary perspective view of a clamp for removably securing the vertical unit to the frame;

Fig. 7 is a fragmentary detailed view of a portion of the winch;

Fig. 8 is a fragmentary side elevational view of the lifting hook, and

Fig. 9 is a fragmentary detailed view of the lateral unit.

In the present embodiment the hoisting apparatus is designed to be removably connected to a frame 10 having a base 11 supporting uprights 10 and a top portion, which in the present instance is known as a cable rack, consisting of parallel members 12 mounted upon lateral projections 13.

A lateral unit 15 is conditioned to be disposed upon the parallel members 12 of the top of the frame and a vertical unit 16 is conditioned to be positioned close to the front of the frame removably secured thereto and also removably secured to the unit 15. The lateral unit has spaced pairs 20 and 21 of channel members disposed 20 in the positions shown in Fig. 1. The channel members of each pair are secured together at the spaced positions by bolts, rivets or the like extending therethrough and through tubular spacers 23. The outer channel member of each 25 pair has a locating lug 24 fixed thereto to engage the farthest member 12 to locate the channel members in place.

Clamps 25, having hook-shaped ends 26 constructed to extend around the lower edge of 30 the farthest parallel member 12, extend upwardly between the channel members in each pair and through apertures in inverted U-shaped members 27 which straddle the channel members in each 35 pair, where the threaded ends of the clamps are connected to wing nuts or the like 28 to removably secure the lateral unit to the frame.

To each pair of channel members 20 and 21 are adjustably secured adjusting screws 30 and 31 having their lower ends fixed to plates 32, 40 held between the channel members in each pair, and extending upwardly through inverted U-shaped members 33. By the aid of a lock nut 34 disposed upon the adjusting screws and conditioned to rest upon the inverted U-shaped members 33 the adjusting screws may be secured to the pairs of channel members 20 and 21 in desired positions. The adjusting screws 30 extend upwardly and between another pair of joined channel members 35 which are supported 45 in any desired adjusted position on the adjusting screws by nuts 36.

The adjusting screws 31 support an angle member 37 in a plane with the upper surface of the channel members 35 by the aid of nuts 38. A 50 pair of channel members 40 mounted for longi-

tudinal adjustment on the angle member 37 and the channel members 35, through the aid of bolts 41 and 44 respectively, have their side portions extending outwardly, as shown in Figs. 1 and 2, and rotatably support sheaves 42 and 43 therebetween. The bolts 41 and 44 extend through inverted U-shaped members which straddle the channel members and between the latter where the bolt 41 extends further through the angle member 37, where it is secured by a nut, and 10 where the bolt 44 extends further between the channel members 35 and a U-shaped member 5 where it is secured by a nut as shown in Fig. 9.

The vertical unit has vertical angle members 45 secured at parallel spaced positions to a base portion 46 and lateral members 47 and 48. In the upper portions of the angle members 45 are disposed apertures 50, as illustrated in Fig. 4, to receive spaced screws 51. Inner plates 52 have threaded apertures for receiving the screws 51. Latches, indicated generally at 54, having portions 55 and 56 secured together by means, such as welding, are supported by the screws 51 and have elongate apertures 57 therein so as to permit vertical movement of the latches with respect to the angle members 45 when the screws are loosened. The portions 55 of the latches are conditioned to engage the lower extremities of the angle member 37 upon each side of a guide block 58, thus limiting vertical movement of the latches, 20 while the portions 56 are conditioned to be moved into engagement with the inner wall of the angle member to hold the vertical angles 45 in close engagement with the outer wall of the angle member 37 when the screws 51 are tightened, thus 30 securing the vertical unit to the lateral unit.

The vertical unit is removably secured to the frame 10 by the aid of clamps 60, shown in Figs. 1 and 6, these clamps having hook-shaped inner portions 61 to extend around a portion of the base 11 and hook-shaped outer portions 62 conditioned to extend around the outer edge of each of the angle members 45, so that through the adjustment of a wing nut 63 threadedly connected to the clamp the hook-shaped portions 61 and 62 may be moved toward each other to firmly hold the angle members 45 of the vertical unit in close engagement with the base 11 of the frame.

A winch, indicated generally at 65, is supported by the lateral members 47 and has a drum 66 upon which a hoisting rope or cable 67 may be wound. The drum 66 is fixed for rotation with a gear 69 which interengages a pinion 70 on a shaft 71. The shaft 71 may be rotated in a suitable manner, for example, through the aid of a crank 72, a pawl 75 and a ratchet 76 normally limiting rotation of the drum in one direction for the winding of the cable 67 upon the drum, and yet permitting, through manual rotation of the pawl, rotation of the drum in the opposite direction to allow the cable to unwind from the drum.

The cable 67 extends upwardly over the sheaves 42 and 43 and downwardly between the parallel members 12, where it is provided with a hook 80 of the type shown in Fig. 7. The hook 80 has a transversely extending portion 81 merging into an upwardly bent end portion 82. The lower end of the portion 81 is split from a position 83, forming the remaining portion 82 into a fork shape to straddle, if desired, a portion of a shelf 85 to be lifted. The shelves have portions along their edges formed of angle members 86 and for this reason the hook 80 is so formed to permit movement of the shelves in substantially vertical paths. A latch 87 pivotally supported by a lug 88 carried

by the hook 80 is movable into and out of position to lock the hook against accidental disengagement of the shelf.

Referring now to the operation of the apparatus, attention is directed to Fig. 1, which illustrates two sets of hoisting units for lifting one type of shelf 85 upwardly relative to the frame 10 to a position where the shelf is to be secured to the frame.

Shelves of this type weigh approximately seven hundred pounds (700 lbs.) and due to the delicate structure of the electrical elements mounted thereupon extreme care must be taken in hoisting the shelves for mounting on the frame. As a rule they are moved into position back of the frame on a suitable conveying means and the cables 67 are lowered so that the hooks 80 may be attached to one of the shelves and locked in place by movement of the latches 87 into the position shown in Fig. 7. The shelf may then be raised by rotation of the winches 65, drawing the cables upwardly and over the sheaves 43 and 42 and downwardly around the drums of the winches. When the shelf has been raised to the desired position it is held against downward movement by the pawls 75 and ratchets 76 until the shelf is secured in place upon the frame. This operation may be repeated, disconnecting the hooks 80 from the first secured shelf and securing them to the next shelf, etc., until all of the shelves have been raised to their desired positions in the frame 10 and secured in place.

The units 15 and 16 may then be transferred to another position, that is, to another frame, and secured in place. This is accomplished by first 35 freeing the cables 67 of the unit 15 and loosely connecting the cables to the upper ends of the unit 16. Let it be assumed, for the purpose of illustration, that only one set of units is desired for the next operation. The unit 16 is then disconnected from the unit 15 by loosening the screws 51 and allowing the latches 54 to be moved downwardly free of the angle member 37. The clamps 60 are then removed by loosening the wing nuts 63 a sufficient distance to permit disconnection of the hook members 61 and 62. The vertical unit 16 is then in condition to be swung free of the lateral unit 15 and moved to one side, for example, to the left, and allowed to lean against the frame 10 until the unit 15 has been released and moved to the next position.

In releasing the unit 15 the clamps 25 are released from the member 12 of the frame which they engage by first loosening the wing nuts 28 a sufficient distance to free the hook-shaped ends 26. The lateral unit is then in a position to be moved to the next frame section, this being accomplished by sliding the base of the unit on the parallel members 12 of the frame. The lateral unit may then be secured in position by tightening the nuts 28 of the clamps 25 to move the hook-shaped portions 26 into close engagement with the adjacent member 12 of the frame. The vertical unit 16 may now be moved into a position adjacent the lateral unit 15, where it may be secured to the frame by the clamps 60 and to the lateral unit by the latches 54.

A single set of units is employed when smaller articles or shelves are to be raised into position. However, with longer shelves, as illustrated in Fig. 1, it is desirable to use two sets of units.

The path of movement of the articles or shelves as they are raised by the cable to be mounted upon the frame may be varied so as to avoid interference of the cable with shelves previously mounted

and to locate the shelf in its desired position as near as possible to the position on the frame where it is to be secured. This adjustment is brought about by loosening the bolts 41 and 44 to loosen the connection of the channel members 40 to allow movement thereof with the sheaves and thus move the path of the portion of the cable carrying the hook 80 toward or away from the vertical unit or the frame until the desired adjustment has been completed, after which the screws 41 may be tightened. It may also be desirable to move the sheave supporting channel members 40 vertically, to vary their positions with respect to the frame to vary the effective height to which the hook 80 may be moved to lift the shelves. This adjustment may be accomplished through the adjustment of the nuts on the adjusting screws 30 and 31, to raise or lower the channel members 35 and the angle member 37 and thus raise or lower the sheave supporting channel members 40. Such adjustments are preferably determined and made prior to the hoisting of articles in positions for mounting but if desired, they may be made during the hoisting of an article.

It will be observed that the cable supporting unit 15 may be disconnected from the vertical unit or the means for moving the cable and may be moved on the frame from one position to the other and removably secured in place. The vertical unit is relieved of its greatest weight when disconnected from its lateral unit and may be easily moved from one position to another. Furthermore, the vertical unit fits flush with the frame, is narrow in width and thickness, and may be used conveniently in narrow places. Furthermore, the two units when assembled form a complete apparatus associated with the vertical frame to move articles upwardly in the frame to desired positions relative thereto and hold the articles, such as the shelves, in substantially the positions they are to assume when mounted upon the frame and thus supporting the shelves until they are suitably mounted.

The embodiment of the invention herein disclosed is illustrative only and may be widely modified and departed from in many ways without departing from the spirit and scope of the invention as pointed out in and limited only by the appended claims.

What is claimed is:

1. An apparatus for hoisting articles comprising a sheave unit including a base supported by and movable to a selected one of a plurality of positions on a vertically positioned frame for supporting articles, front and back sheaves, an element to rotatably support the sheaves, and means to secure the element to the base to position the front sheave in an overhanging position in front of the frame and the back sheave above the frame, a vertical unit subsequently movable to a position adjacent the sheave unit and including a cable moving means, a cable, connected to the cable moving means, extending upwardly and over the front and back sheaves and having a member to engage an article movable vertically upon movement of the cable to a predetermined portion of the frame where the article is to be supported.

2. An apparatus for hoisting articles comprising a sheave unit including a base supported by and movable to a selected one of a plurality of positions on a vertically positioned frame for sup-

porting articles, front and back sheaves, an element to rotatably support the sheaves, and variable means to secure the element to the base to locate the front sheave in variable overhanging positions in front of the frame and the back sheave in variable positions above the frame, a vertical unit subsequently movable to a position adjacent the sheave unit and including a cable moving means, means to removably secure the vertical unit to the frame in the said position adjacent the sheave unit, and a cable, connected to the cable moving means, extending upwardly and over the front and back sheaves and having a member to engage an article movable vertically upon movement of the cable to a predetermined portion of the frame where the article is to be supported.

3. An apparatus for hoisting articles comprising a sheave unit including a base supported by and movable to a selected one of a plurality of positions on a vertically positioned frame for supporting articles, front and back sheaves, an element to rotatably support the sheaves, and means to secure the element to the base to position the front sheave in an overhanging position in front of the frame and the back sheave above the frame, a vertical unit subsequently movable to a position adjacent the sheave unit and including a cable moving means, a cable, connected to the cable moving means, extending upwardly and over the front and back sheaves and having a member to engage an article movable vertically upon movement of the cable to a predetermined portion of the frame where the article is to be supported, and means to removably connect the vertical unit to the sheave unit.

4. An apparatus for hoisting articles comprising a sheave unit including a base supported by and movable to a selected one of a plurality of positions on a vertically positioned frame for supporting articles, front and back sheaves, an element to rotatably support the sheaves, and means to secure the element to the base to position the front sheave in an overhanging position in front of the frame and the back sheave above the frame, a vertical unit subsequently movable to a position adjacent the sheave unit and including a cable moving means, a cable, connected to the cable moving means, extending upwardly and over the front and back sheaves and having a member to engage an article movable vertically upon movement of the cable to a predetermined portion of the frame where the article is to be supported, and means to removably connect the vertical unit to the element of the sheave unit.

5. An apparatus for hoisting articles comprising a sheave unit including a base supported by and movable to a selected one of a plurality of positions on a vertically positioned frame for supporting articles, front and back sheaves, an element to rotatably support the sheaves, and variable means to secure the element to the base to locate the front sheave in variable overhanging positions in front of the frame and the back sheave in variable positions above the frame, a vertical unit subsequently movable to a position adjacent the sheave unit and including a cable moving means, a cable, connected to the cable moving means, extending upwardly and over the front and back sheaves and having a member to engage an article movable vertically upon movement of the cable to a predetermined portion of the frame where the article is to be supported, and means to removably connect the vertical unit to the element of the sheave unit.

6. An apparatus for hoisting articles comprising a sheave unit including a base supported by and movable to a selected one of a plurality of positions on a vertically positioned frame for supporting articles, means to removably secure the base to the frame at the selected position, front and back sheaves, an element to rotatably support the sheaves, and means to secure the element to the base to position the front sheave in an overhanging position in front of the frame and the back sheave above the frame, a vertical unit subsequently movable to a position adjacent the sheave unit and including a cable moving means, means to removably secure the vertical unit to the frame in the said position adjacent the sheave unit, and a cable, connected to the cable moving means, extending upwardly and over the front and back sheaves and having a member to engage an article movable vertically upon movement of the cable to a predetermined portion of the frame 20 where the article is to be supported.

7. An apparatus for hoisting articles comprising a sheave unit including a base supported by and movable to a selected one of a plurality of positions on a vertically positioned frame for supporting articles, front and back sheaves, an element to rotatably support the sheaves, and variable means to secure the element to the base to locate the front sheave in variable overhanging positions in front of the frame and the back sheave in variable positions above the frame, a vertical unit subsequently movable to a position adjacent the sheave unit and including a cable moving means, a cable, connected to the cable moving means, extending upwardly and over the front and back sheaves and having a member to engage an article movable vertically upon movement of the cable to a predetermined portion of the frame where the article is to be supported, and means to removably secure the vertical unit to the frame.

LLOYD R. KALMBACH.
